(57) **CLAIM**

The ornamental design for a display screen with animated graphical user interface, as shown and described.

DESCRIPTION

FIG. 1 is a front view of a first image of a display screen with animated graphical user interface showing a first Embodiment of our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of a first image of a display screen with animated graphical user interface showing a second embodiment of our new design;

FIG. 9 is a front view of a second image thereof;

FIG. 10 is a front view of a third image thereof;

FIG. 11 is a front view of a fourth image thereof;

FIG. 12 is a front view of a fifth image thereof;

FIG. 13 is a front view of a sixth image thereof; and,

FIG. 14 is a front view of a seventh image thereof.

The appearance of the animated graphical user interface sequentially transitions between the images shown in FIGS. 1-7. The appearance of the animated graphical user interface sequentially transitions between the images shown in FIGS. 8-14. The process or period in which one image transitions to another image forms no part of the claimed design. The outermost broken lines showing a display screen and all other broken lines illustrating portions of the graphical user

(Continued)

interface are included for the purpose of illustrating portions of the article and form no part of the claimed design. The dash-dot lines represent the boundary between the claimed design and unclaimed design and form no part of the claimed design.
